BOTTLE HOLDER

James B. Carmichael, Davis, Okla.

Application October 9, 1939, Serial No. 298,660

6 Claims. (Cl. 120—73)

This invention aims to provide a simple but useful device for holding a container, such as an ink bottle, on a support, for instance a table or desk, in upright position and against accidental overturning. The invention aims, further, so to construct the container band and the housing which receives it, that the band will accommodate bottles of large diameter, the housing or casing being kept short. A further object of the invention is to provide novel means whereby the band may be held in adjusted, outwardly extended positions, with respect to the housing, at the will of an operator.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawing:

Fig. 1 shows in perspective, an article constructed in accordance with the invention, the device being in closed or inoperative position;

Fig. 2 is a side elevation wherein the band has been advanced, to retain a bottle;

Fig. 3 is a top plan of the structure as shown in Fig. 2;

Fig. 4 is a vertical section on the line 4—4 of Fig. 2;

Fig. 5 is a horizontal section on the line 5—5 of Fig. 4;

Fig. 6 is a longitudinal section, parts being broken away;

Fig. 7 is a longitudinal section showing a modification.

The device forming the subject matter of this application may be made of any desired material, such as metal. It embodies a box-like housing 1 which is open at the bottom and at the forward end. The housing 1 has an outstanding foot flange 2, adapted to receive securing elements 3, attaching the housing 1 to a support 4, such as a table or desk. In the horizontal section, the housing 1 is U-shaped, as Fig. 5 will show.

Partitions 5 are secured to the top of the housing 1 and extend downwardly about half the

height of the housing. The partitions 5 define guideways 6, each extended continuously about the housing 1, from the forward end of the housing. The guideways 6 are disposed parallel to the upright wall of the housing 1.

The numeral 7 marks a container-band, which is a composite structure. The container-band 7 comprises an intermediate plate 8, which may be high enough to form a closure for the forward end of the housing 1, the lower edge of the plate 8 being adapted to ride on the support 4, as the container-band 7 is thrust backwardly into the housing 1, as indicated in Fig. 1, or withdrawn partially from the housing, as disclosed in Fig. 2.

The container-band 7 embodies arms 9, preferably made of metal, and having, approximately, the resiliency of a metal rule-tape of known construction, adapted to be wound into a roll in a case. The arms 9 of the container-band 7 extend backwardly into the guideways 6 of the housing 1 and are slidable in the guideways. It may here be noted that the aforesaid continuity of the guideways 6 permits the arms 9 to be long enough to accommodate a container of large diameter, when the band 7 is advanced out of the housing 1, the housing being of small length, so that it will not take up much room on a desk. Figure 5 shows that the arms 9 of the container-band 7 may be so long that they will extend past each other, in opposite directions, at the back of the housing 1, and along the sides thereof.

In order to limit the ultimate outward advancement of the container-band 7, its arms 9 terminate in projections or hooks 10, adapted to engage stops 11 on the wall of the housing 1 and on the partitions 5, at the forward end of the housing. A means is provided whereby the operator can cause the container-band 7 to be held in any position to which it may have been advanced out of the housing 1. That means may be of various sorts, as the manufacturer may prefer, but the means delineated in the drawing is satisfactory and preferred. It comprises a tiltable keeper plate 12, disposed transversely of the housing 1, and having terminal shafts 14, mounted to rock in the side walls of the housing. For the convenient manipulation of the keeper plate 12, from a place without the housing 1, one of the shafts 14 is supplied with a turning button 15. The lower edges of the arms 9 of the container band 7 are notched to form racks 16 therewith the keeper plate 12 is adapted to engage, as shown in Fig. 6. For the accommodation of the keeper plate 12, and in order to enable

it to engage with the racks 16, certain of the partitions 5 may be correspondingly notched, an observation which will be understood readily when Fig. 4 of the drawing is noted.

5 In practical operation, the keeper plate 12 is turned to a horizontal position, so that the arms 9 of the container-band 7 can be advanced over it. By means of the closure plate 8, the container-band 7 is drawn out of the housing 1, 10 until an ink bottle 17 can be received between the resilient arms 9, as shown in Figs. 2 and 3, the bottle resting on the support 4. The keeper plate 12 is tilted until it engages the racks 16 and, thus, the parts are held in the position 15 shown in Fig. 2. The keeper plate 12 and the racks 16 also are available to hold the member 8 in closed position, as shown in Fig. 6. Since the arms 9 of the container-band 7 are resilient, they will accommodate bottles of different diameters and shapes, if the container-band is advanced sufficiently out of the housing 1.

The holding mechanism represented by the racks 16 and the keeper 12 may be dispensed with. Such a construction is shown in Fig. 7. 25 In that figure, parts hereinbefore described have been designated by numerals already used, with the suffix "a".

The device is simple in construction, but will be found thoroughly advantageous for maintaining an ink bottle or the like in an upright position, on a support, against overturning. Figure 1 shows that the device, when not in use, takes up little compass on a desk, the device detracting nothing from the appearance of the 35 desk or table to which it is attached.

What is claimed is:

1. In a device for holding a container on a support, in upright position and against accidental overturning, a housing, and a container-band comprising arms mounted for in and out sliding movement with respect to the housing, the arms being resilient, to conform to containers of different diameters. 40

2. In a device for holding a container on a support, in upright position and against accidental overturning, a housing, a container-band comprising arms mounted for in and out sliding movement with respect to the housing, and means under the control of an operator for holding the band in adjusted, outwardly extended positions with respect to the housing. 5

3. A device of the class described, constructed as set forth in claim 1, and wherein the band embodies a closure for one end of the casing.

4. A device of the class described, constructed as set forth in claim 2, and wherein said means embodies racks on the arms, and latch mechanism carried by the housing and cooperating 15 with the racks.

5. In a device for holding a container on a support, in upright position and against accidental overturning, a housing having guides each extended continuously about the housing 20 from one end of the housing, and a container-band comprising arms entering said end of the housing and slideable in the guides, the continuity of the guides permitting the arms to be long enough to accommodate a container of large 25 diameter, when the band is advanced out of the housing, and enabling the housing to be of small length.

6. In a device for holding a container on a support, in upright position and against accidental overturning, a housing having guides each extended from one end of the housing, along one side of the housing and transversely of the back of the housing, and a container-band comprising arms entering said end of the housing 30 and slideable in the guides, the arms extending in opposite directions, transversely of the back of the housing, and being long enough to accommodate a container of large diameter 35 when the band is advanced out of the housing, the length of the housing being thereby reduced. 40

JAMES B. CARMICHAEL.
